CLAIM

The ornamental design for a cooking pan, as shown and described.

DESCRIPTION

1. Cooking pan

1.1 : Perspective

1.2 : Front

1.3 : Left

1.4 : Top

1.5 : Bottom

1.6 : Cross sectional

1.7 : Cross sectional

The broken lines form no part of the claimed design; the rear view is omitted as it is identical with the front view; the right side view is omitted as it is identical with the left side view; 1.6 is a cross sectional view taken along the line 1.6-1.6 in 1.4; and 1.7 is a cross sectional view taken along the line 1.7-1.7 in 1.4.

1 Claim, 7 Drawing Sheets
